UNITED STATES PATENT OFFICE.

HENRY RICHARD SEIFERT, OF ELLSWORTH, WISCONSIN.

PISTON-RING.

1,369,362.

Specification of Letters Patent. Patented Feb. 22, 1921.

Application filed May 2, 1917. Serial No. 165,933.

To all whom it may concern:

Be it known that I, HENRY RICHARD SEIFERT, a citizen of the United States, residing at Ellsworth, in the county of Pierce and State of Wisconsin, have invented certain new and useful Improvements in Piston-Rings; and I do hereby declare the following to be a full, clear, and exact description of the invention, such as will enable others skilled in the art to which it appertains to make and use the same.

This invention relates to improvements in piston rings, particularly designed for use in connection with internal combustion engines, and the invention has for its primary object to provide an improved terminal connection between the ends of a split ring to insure against leakage of the fluid past the joint.

With this and other objects in view, the invention consists in the novel construction, combination and arrangement of parts as will be hereinafter specifically described, claimed and illustrated in the accompanying drawing, in which:

Figure 1 represents a plan view of the improved piston ring,

Fig. 2 represents a fragmentary perspective view of the joint between the terminals of the ring,

Fig. 3 represents a transverse sectional view on the line 3—3 of Fig. 2,

Fig. 4 represents a transverse sectional view on the line 4—4 of Fig. 2, and

Fig. 5 represents a fragmentary perspective view of one terminal of the ring.

Referring to the drawing in detail, wherein similar reference numerals designate corresponding parts throughout the several views, the numeral 5 indicates the body of the ring which is rectangular in cross section, as usual, and is split to provide overlapping terminals 6. As in the ordinary types of piston rings, the inherent resiliency of the material from which the ring is constructed normally maintains the ring in expanded condition and it is designed to be contracted when placed in the groove of the piston (not shown) so as to snugly fit against the inner surface of the wall of the cylinder.

Each of the overlapped ends 6 is reduced to provide a tongue 7 and the inner, or ad-

jacent surfaces, of the tongues are curved to present opposed substantially semi-cylindrical surfaces 8. By reducing the terminals of the split ring to provide the tongues 8 shoulders 9 are formed at the bases of the tongues which are designed to limit the contracting movement of the ring. The opposed side faces of the ring are formed with recesses 10 of concave formation to receive and provide sockets for the tongues 8, which are slidably received in recesses 10.

When the ring is applied to a piston and positioned in the cylinder of an engine, it expands against the inner surface of the wall of the cylinder and engages the walls of the groove in the piston, so as to prevent leakage of the fluid between the cylinder wall and piston. The tongues 7, fitting in the recesses 10, provide a seal to prevent fluid from leaking through the joint between the terminals of the ring and the pressure from the top or bottom of the piston directed against the tongue 7 which is presented to the pressure, causes said tongue to be firmly pressed into the recess 10 to increase the security of the seal.

The interlocking tongues and grooves are segmental in cross section and are therefore devoid of square corners which form pockets in which carbon lodges. In preventing the deposit of carbon the tongues fit flatly in the grooves which disposes the outer sides of the end portions of the rings flush and thereby prevents scoring of the cylinders.

What I claim is:

A piston ring comprising a body consisting of a strip of material of uniform transverse breadth throughout its length, said strip having overlapping end portions each end portion having an extremity provided with a transversely convex inner surface and each portion being provided adjacent its extremity with a recess having a transversely concaved bottom wall, said recesses adapted to snugly receive the said extremities.

In testimony whereof I affix my signature in presence of two witnesses.

HENRY RICHARD SEIFERT.
